COMBINATION AMALGAM CARRIER AND PLUGGER

Robert B. Thurman, Sparta, Tenn.

Application July 3, 1953, Serial No. 365,821

2 Claims. (Cl. 32—60)

The present invention relates to a combination amalgam carrier and plunger and it consists in the combinations, constructions and arrangements of parts herein described and claimed.

Generally there is provided a device which is adapted to be used for picking up pieces of amalgam and transferring them to cavities in teeth to be filled and which device may then be utilized as a plunger for forcing such piece of amalgam into the cavity. The device contains many novel features including a novel means for transferring force applied to a plunger to the working end of the device, such end also being curvular to provide easy access to cavities particularly in the molars. Novel locking means is provided for locking a plunger forming a part of the invention in its outward position in the working end of the device whereby the same may be used as a plunger.

It is accordingly an object of the invention to provide a novel combined amalgam carrier and plunger.

Another object of the invention is to provide, in a device of the carrier set forth, a novel curvular neck portion forming a part of the invention.

Another object of the invention is to provide, in a device of the character set forth, a novel lock forming a part of the invention.

A further object of the invention is to provide, in a device of the character set forth, novel means for transferring force from one part of the device to another, such means forming a part of the invention.

Other and further objects of the invention will become apparent from a reading of the following specification taken in conjunction with the drawing, in which:

Figure 1 is a side elevational view of an embodiment of the invention.

Figure 2 is a view similar to Figure 1 but broken away to disclose the interior mechanisms of the device.

Figure 3 is a view similar to Figure 2 but showing an operating handle forming a part of the invention in extended position.

Figure 4 is an enlarged fragmentary vertical sectional view of a cap and allied structure forming a part of the invention, with the plunger retracted.

Figure 5 is an enlarged fragmentary sectional view with the plunger extended.

Figure 6 is a section taken on line 6—6 of Figure 1.

Figure 7 is a section taken on line 7—7 of Figure 1.

Referring more particularly to the drawing, there is shown therein a device of the character set forth comprising an elongated hollow cylinder 10 to whose forward end is integrally connected a neck generally indicated at 11 and having a rearward portion 12 which extends concentrically with the cylinder 10 and a forward curvular portion 13 whose free end 14 extends perpendicularly to the longitudinal axis of the cylinder 10.

A cap is generally designated at 15 and consists of a centrally apertured knurled head 16 and a reduced exteriorly threaded portion 17 adapted to be threaded into the rearward end of the cylinder 10. The head 16 is provided with a pair of diametrically opposed bayonet slots 18 for the reception therein of a pin 19 which extends diametrically through a rod 20 which, in turn, extends slidably and centrally through the head 16 into the interior of the cylinder 10.

Forward portion of the rod 20 is reduced, as shown at 21 thus providing a shoulder 22 and the reduced portion 21 extends into the rear portion of the neck 11. A compression spring 23 surrounds the reduced portion

21 and bears against the shoulder 22 at one of its ends and against the forward wall 24 of the cylinder 10 at its other end.

The outer or free end of the rod 20 is provided with an actuating button 25. Threaded upon the outer side of the portion 14 of the neck 11 is a work head 26 which tapers inwardly toward its outer end 27. The head 26 is provided with a centrally located longitudinally extending passage 28 in its outer end and with a cylindrical chamber 29 in its inner end.

A piston 31 is slidably mounted in the passage 28 and terminates in the chamber 29 with an enlarged cylindrical head 32. A plurality of balls 34, preferably formed of hardened steel, is mounted in the neck 11 and extends from the forward end of the reduced portion 21 of the rod 20 to the member 32.

In operation, it will be apparent that when it is desired to transfer amalgam from a source of supply to a tooth cavity, the pin 19 will first be disengaged from the bayonet slots 18 by a simple twist of the operating handle 25 whereupon the spring 23 will act to move the rod 20 outwardly of the piston 10 thus permitting an inward movement of the piston 31 into the head 26. This leaves a space in the outer end 27 of the head 26 between the outer end of the piston 31 and the extreme outer end 27 of the head 26. The head 26 may now be forced into the supply of amalgam and a portion thereof will be held within the space just referred to whereupon the head 26 may now be moved to a point adjacent or in the cavity to be filled and by pressing inwardly upon the operating handle 25 the rod 20 will be moved inwardly and consequently the reduced portion 21 thereof will impinge against the series of balls 34 which, in turn, will impinge against the member 32 and thus force the piston 31 outwardly of the head 26 as shown. To use the device as a plunger, the rod 20 may now be locked within the bayonet slots by moving the pin 19 therein and twisting the same in conventional manner. This will, in turn, act to hold the piston 31 in its outer position as just described whereupon the device may be used as a plunger for the amalgam to force the same in conventional manner into the aforesaid cavity.

It will be apparent that the particular curvature of the neck 11 will allow the device to be utilized in the filling of tooth cavities which are normally difficult if not impossible to reach by conventional tools. It will also be seen that the series of balls 34 will act to transfer force applied to the handle 25 to the piston 31 as above described.

While but one form of the invention has been shown and described herein, it will be readily apparent to those skilled in the art that many minor modifications may be made without departing from the spirit of the invention or the scope of the appended claims.

What is claimed is:

1. A device of the character described comprising a hollow cylinder having a forward wall, a neck formed integrally with said wall and having a rear portion concentric with said cylinder and a curved forward portion, said neck and said wall having a passageway therethrough, a work head removably mounted on the free end of said neck, a piston reciprocally mounted in the outer end of the work head, a knurled head removably mounted on the rear end of said cylinder, a rod reciprocally mounted in said knurled head and having a reduced portion extending into said passageway, means for imparting movement from said rod to said piston, a handle on the outer end of said rod, said reduced portion forming a shoulder with the remainder of said rod, and a compression spring surrounding said reduced portion and bearing against said shoulder and said wall, said rod being provided with a pin extending transversely therethrough adjacent said handle, and within said knurled head is provided with a pair of bayonet slots for receiving said pin whereby to lock said rod in its innermost position.
2. A device of the character described comprising a hollow cylinder having a forward wall, a neck formed integrally with said wall and having a rear portion concentric with said cylinder and curved forward portion,

said neck and said wall having a passageway therethrough, a work head removably mounted on the free end of said neck, a piston reciprocally mounted in the outer end of the work head, a knurled head removably mounted on the rear end of the cylinder, a rod reciprocally mounted in said knurled head and having a reduced portion extending into said passageway, means for imparting movement from said rod to said piston, and a handle on the outer end of said rod, said means com-
